UNITED STATES PATENT OFFICE.

JOSEPH C. FULLER, OF PERTH AMBOY, NEW JERSEY.

STARTING MECHANISM FOR STEAM-AUTOMOBILES.

1,234,326.

Specification of Letters Patent. Patented July 24, 1917.

Application filed May 19, 1916. Serial No. 98,706.

To all whom it may concern:

Be it known that I, JOSEPH C. FULLER, a citizen of the United States, residing in Perth Amboy, New Jersey, have invented 5 certain new and useful Improvements in Starting Mechanism for Steam-Automobiles, of which the following is a specification.

My invention relates to a device by which the starting of steam automobiles, or, in 10 fact, any mechanism in which steam is the moving force, is facilitated. Hitherto one of great drawbacks to the use of a steam engine as the prime mover for automobiles, motor boats, and the like, has been the difficulty experienced in starting the fire and the 15 annoyance attendant upon getting up steam pressure in the boiler especially with kerosene as the fuel. My invention aims to coordinate the various functions or events that 20 are necessary in firing up a steam boiler, utilizing a heavy liquid hydro-carbon as the fuel, and to make the accomplishment of these functions or events automatic through the utilization of suitable apparatus.

For purposes of illustration I have shown 25 my invention as applied to the mechanism of a well-known steam automobile of American manufacture, namely, the Stanley Steamer. Certain types of this vehicle are 30 adapted to burn kerosene as a fuel, this liquid being much more inexpensive than the gasoline, or the other lighter hydro-carbons. Kerosene, however, possesses the disadvantage of not readily vaporizing without 35 the application of external heat, and hitherto it has been the practice in firing up the boilers of Stanley Steamers using kerosene to utilize an acetylene torch or some other similar device, for heating the pilot 40 burner under the boiler to such a temperature that the gasoline passing through the burner would vaporize and burn, thus making it possible to heat up the main burners under the boiler and so eventually cause 45 them to vaporize their fuel. This has been a hand-controlled operation, requiring considerable patience and experience, in order to carry it out satisfactorily. It usually takes upward of three or four minutes to 50 bring the main burners into such condition that they are ready to vaporize the fuel and perform their proper function. My invention is designed to overcome all the disadvantages inherent in the manual operations 55 hitherto necessary in firing up a boiler in this manner.

In the accompanying drawings, which form a part of this specification, Figure 1 is a diagrammatic plan view showing the entire mechanism. Fig. 2 is a detail plan view of the actuating mechanism, parts being shown in section. Fig. 3 is an elevation of the mechanism shown in Fig. 2, certain parts being shown in section for the purpose of clearness. Fig. 4 is an elevation of 60 a modified form of actuating mechanism. Fig. 5 is a detail end view of a portion of this mechanism. Fig. 6 shows a view of a modified form of burner mechanism.

Referring to the drawings in detail, the 70 numeral 1 designates the main kerosene storage tank, from which, when the automobile is normally operating, the fuel passes through pipes 2 and 3 the power-driven kerosene pump 4 which takes the fuel thus 75 fed to it and pumps it through pipe 5, check valve 6, pipe 7, automatic relief valve 8, pipe 9, main burner valve 10, through various automatic valves and coils indicated by the dotted lines 11, through pipe 12, main 80 burner tube 13, to the main burner 14. The kerosene issues from the burner as a vapor, which mixes with a suitable quantity of air and passes through the burner casting 15, burning in the space 16 under the boiler 17. 85 It will be seen that since the tube 13 is directly in the path of the flame, the kerosene is heated on its way to the main burner and thus a continuous operation is insured. The problem is, then, to heat this main burner 90 tube to such a temperature that kerosene passing through it will be in condition to be vaporized and will thus readily burn.

Through the action of the pump 4 the 95 kerosene is maintained under pressure in that part of the lines starting with the pipe 5, by virtue of the check valve 6, which prevents its return through the pump, and the air pressure domes 18 which communicate 100 with the pipe 9. When the pressure in the pipe 9 exceeds that which is desirable for normal operation, the excessive pressure opens the automatic relief valve 8, allowing the kerosene to return through pipe 19 to the storage tank. By means of this construction the pump 4 may be continuously 105 operated and will maintain a constant pressure in the line without danger of excessive pressure building up.

The parts of the mechanism so far described form no feature of my invention, 110 but are in well known use upon a large num-

ber of Stanley Steamers already in operation.

Supposing that there is no fire under the boiler 17 and that the parts are all cold, it is necessary to initiate a series of events which will produce continuous vaporization of the fuel. This is accomplished, according to my invention, in the following manner: The operator first pulls out the ring 20 which closes an electric switch 21. A circuit is thus formed from the storage battery 22 or other source of electrical energy through wire 23, switch 21, wire 24, motor 25, wire 26, and wire 27. This starts the motor, the shaft 28 of which immediately begins to revolve, turning with it gear 29. This gear in turn rotates the gear 30, which is connected by means of a crank 31 to the kerosene pump 32, which immediately draws kerosene from the tank 1, through the pipe 33 and pumps it through pipe 34 and check valve 35 into the main kerosene line which, under normal conditions of operation, is fed from the main kerosene pump 4. It will, of course, be appreciated that at this moment the kerosene pump 4 is not in operation, since the engine of the vehicle, to which it is geared, is not running. This series of events makes certain a supply of kerosene under pressure in the main kerosene line. Scarcely has the shaft of the motor started to rotate when automatic means, which will later be described in detail, closes a switch 36, completing a circuit from the storage battery through wire 23, switch 21, wire 24, wire 37, switch 36, wire 38, heating coil 39, wire 40 and wire 27. This causes the current to pass through the electric heating coil 39, which surrounds a burner tube 41 leading to a burner 42, which may be adjacent to the main burner 14. This coil may be of any suitable and well-known construction and need not be described here in detail.

After a suitable interval has elapsed, which will depend upon the current available from the storage battery, and other factors involving the dimensions of the parts, the burner tube 41 will be heated to such a temperature that any kerosene that may be forced through it will be heated to a point where it will immediately vaporize upon issuing from the burner 42. At this instant automatic means (later to be described) opens valve 43, permitting kerosene under pressure to flow from the pipe 9 through the pipe 44, passing the manually operated valve 45, which has been opened by the operator before closing the switch 21, continues through pipe 46, valve 43 and pipe 47 into the burner tube 41. The kerosene under pressure thus passes through the burner tube, is heated and leaves the burner 42, vaporized and in condition to be ignited. Simultaneously with the opening of the valve 43, the switch 48 is automatically

closed. This closes a circuit from the battery 22, through wire 23, switch 21, wire 24, switch 48, wire 49, primary of spark coil 50, wire 51, and wire 27. A high tension electric current immediately flows from the secondary of the coil, through wires 52 and 53, to the spark plug 54, thus producing a succession of high tension electric sparks immediately above the burner casting 15. The hot kerosene vapor mixed with a suitable quantity of air, rushes through the burner casting and is ignited by the sparks produced at the spark plug. The flame thus formed has two effects: first, to heat the water in the boiler 17, and, second, to heat rapidly the main burner tube 13. After a requisite interval, which may be only a few seconds, the switch 48 is automatically opened, thus breaking the circuit to the spark coil, and no more sparks are produced at the spark plug since the flame is now self-supporting. After the flame from the burner 42 has impinged upon the main burner tube 13 for a few moments, the latter will become so hot that kerosene may be forced through it and will be vaporized as it issues from the burner 14. When this moment arrives the mechanism automatically opens the valve 55 which allows kerosene under pressure to pass through pipe 56, 95 through the various controlling devices represented by the dotted lines 11, and so on through the pipe 12 to the main burner tube. The controlling devices referred to include the steam automatic valve and low water 100 automatic valve with which vehicles of this type are now regularly equipped.

In passing through this main burner tube 13, the kerosene is heated to a high temperature, and emerges from the burner 14 in the form of a vapor, which ignites upon reaching the flame produced by the burner 42. At this instant, the flame from the main burner 14 becomes self-sustaining and the switch 36 is automatically opened, thus 105 breaking the circuit in which is the heating coil 39. Simultaneously the valve 43 is closed, thus shutting off the flow of kerosene through the burner tube 41 and the flame at the burner 42 dies out, but the flame at the 115 burner 14 continues.

Upon hearing the roaring noise which is produced by the ignition of the fuel issuing from the main burner or burners 14, the operator manually opens the main burner 120 valve 10. A few moments after the valve 55 is automatically opened, it is automatically closed, and then the switch 21 automatically opens, thus stopping the motor and leaving the parts in their initial position except for 125 the fact that kerosene under pressure is now flowing through the main line to the valve 10 and thence to the main burner 14, where it continues to burn and maintain steam in the boiler. As soon as the steam engine is 130

started, the pump 4 will begin to operate and will maintain the pressure in the kerosene line, but, in any event, the air domes 18 are of such capacity that even after the 5 pump 32 has stopped, and before the pump 4 begins operating, they will maintain a sufficient pressure in the kerosene line for a considerable length of time.

In Figs. 2 and 3 I have shown one form of mechanism by which the sequence of events above referred to may be caused to take place automatically. Upon the shaft 28 of the motor 25 is mounted a worm 57 meshing with a worm wheel 57, which is mounted 15 upon a cross-shaft 58. This shaft carries a worm 59 which meshes with a worm wheel 60 mounted upon a shaft 61. It will be seen that through this double reduction, the speed of the shaft 61 may be made very 20 small, preferably so that it will revolve only once in an interval of several minutes. When the operator pulls out the ring 20, he closes the contacts 62 of the switch 21, these contacts being normally kept open by a 25 spring 63, as clearly indicated in Fig. 3. Just as soon as these contacts close, the motor shaft starts rotating and through the mechanism above described, slowly turns the shaft 61, which carries with it the disk 30 64 in the direction indicated by the arrow in Fig. 3. As soon as the disk starts to rotate, its circular periphery engages the end of the plunger 65 and maintains the switch contacts 62 closed, keeping the spring 63 35 under compression. It will be seen that these contacts will automatically separate when the disk 64 reaches such a position that the plunger 65 can enter the slot 66 cut in the periphery of the disk 64. Consequently, 40 the switch 21 will remain closed throughout a complete revolution of the disk 64. Continued rotation of the shaft 61 brings a cut-away portion of the cam 67, which is mounted on the shaft, into register with the cam follower 68, mounted upon the plunger 69. The spring 70 forces the follower into the 45 cut-away portion of the cam 67 and closes the contacts of the switch 36. At the proper moment teeth cut on the face of the disk 71, which may be called a mutilated gear and 50 which is secured to the shaft 61, mesh with gear 72, thus rotating the shaft 73, which is connected to the valve stem 74 of valve 43. Simultaneously the switch 48 is closed when 55 a cut-away portion of the cam 75 comes into register with the cam follower 76 mounted on the plunger 77 actuated by the spring 78. It will be appreciated that the time of opening and closing the switches 36 and 48 may 60 be accurately controlled by the position and extent of the cut-away portions of the cams 67 and 75, respectively.

The mechanism for turning the valve stem 79 of the valve 55 is similar to that described 65 in connection with the valve 43 and consists

of a shaft 80 carrying a gear 88 which is adapted to be rotated by a mutilated or segmental gear 89 also mounted on the shaft 61. To effect the closing of the valve 43 I provide a mutilated gear 90 mounted on the 70 shaft 61 and which meshes with a gear 91 upon a shaft 92 which is connected to the shaft 73 by means of the gears 93 and 94. It will be obvious that by this arrangement 75 the engagement of the teeth upon the mutilated gear 90 with the gear 91 at the proper time will rotate the valve stem 74 in the reverse direction, that is, the direction necessary to close the valve. Similar means is provided in connection with the other automatic valve and consists of a mutilated gear 95 meshing with a gear 96 on shaft 97 which is connected to the shaft 80 by means of gears 98 and 99.

In order to form a more or less yieldable 80 means for closing the valves, since they will not always seat at the same point, but at the same time mechanism which will positively open them, I provide the device shown in section in Fig. 2. When the valve 55 is to 85 be opened, power is applied to its valve stem 79 through the shaft 80 which carries on its end a crown ratchet member 100 meshing with a crown ratchet member 101 rigidly fixed to the stem 79. The member 100 is 90 splined to the end of the shaft 80 so as to be capable of sliding longitudinally upon the shaft while always rotating with it. The members 100 and 101 are normally kept 95 in mesh by means of a spring 102. It will 100 be seen that when the shaft 80 is moved in the direction to open the valve, its rotation will be positively applied to the stem 79 and the valve will thus be opened without question. When the shaft 80 is rotated in the 105 opposite direction to close the valve, the ratchet member 100 may recede back along the shaft 80 against the force of the spring 102 as the teeth of the two ratchet members ride over each other. Power is then applied 110 to the valve stem 79 by means of a spider spring 103, mounted on the end of the shaft 80 and in frictional engagement with a disk 104 fixed to the end of the stem 79. By means of this frictional engagement, 115 the valve is closed, but when it reaches its seat, no damage can be done, since a slight continued rotation or overtravel of the shaft 80 will simply cause the spider spring to slip along over the surface of the disk 104. 120 This construction, therefore, provides a means for closing the valve, while affording a positive drive for opening it. Similar means is provided in connection with the shaft 73 and the valve stem 74.

In Figs. 4 and 5 I have shown a modified mechanism for controlling the opening and closing of the valves 43 and 55. In this form, the motor 25 carries a worm 105 keyed 125 to the shaft 28. This worm meshes with a 130

worm wheel 106 mounted on a shaft 107 carrying the worm 108, which drives a worm wheel 109 mounted on a shaft 110. The shaft 110 also carries a pair of cam disks 111 and 112. The cam 111 operates a cam follower 113 mounted on a rod 114, pivoted at 115 to a bar 116, which is mounted so as to be capable of freely oscillating about a shaft 117. A segmental gear 118 is also loosely mounted on the shaft 117 and is caused to oscillate through the agency of a rod 119 connected by a ball and socket joint 120 to a rod 121 connected to the strap 122 of the eccentric 123 mounted on the shaft 107. The segmental gear 118 carries a pawl mechanism 124 pivoted to the face of the gear 118 and provided with the dogs 125 and 125^a, which are adapted to engage the teeth of a gear 126 keyed to the shaft 117. The dogs are normally held away from the teeth by the face 127 of an enlarged portion of the bar 116. It will be seen that with the parts in the position shown in Fig. 4, the segmental gear and the dogs oscillate back and forth without causing any displacement of the gear 126 and the shaft 117. When, however, the raised portion 128 of the cam 111 engages the follower 113, the bar 116 will be thrown to the left, the dog 125^a will be permitted to engage the teeth of the gear 126 and by reason of the oscillation of the dog and of the segmental gear upon which it is mounted, the gear 126 will be moved step by step in the direction of the arrow in Fig. 4. This action will continue as long as the raised portion 128 is in engagement with the follower 113 and may be utilized either to open or close the valve through the medium of the yieldable mechanism illustrated in Figs. 2 and 3. On the other hand, when the cutaway portion 129 of the cam 111 is in contact with the follower 113, the bar 116 will be moved to the right through the agency of the spring 130, and the dog 125 will drop into engagement with the teeth of the gear 126. Springs 131 are provided for forcing the ratchet dogs into engagement with the teeth. The engagement of the dog 125 with the gear 126 will move the gear in a counter-clockwise direction owing to the oscillation of the dog and the segmental gear 118. This provides a means for rotating the shaft 117 in the reverse direction.

The other valve stem may be operated through similar mechanism consisting of a segmental gear 132, the teeth of which are in mesh with the teeth of the segmental gear 118. This gear is loosely mounted on a shaft 133 which also carries the controller 134 for the dogs 135 and 136, which are urged toward the teeth of the gear 137 keyed to the shaft 133, by means of the springs 138. This controller is actuated by a bent lever 139 connected to the follower 140 of the cam 112, the spring 141 being utilized to keep the fol-

lower in contact with the face of the cam. The follower is shown in contact with the raised portion 142 of the cam which forces the lever 139 and the controller 134 to the right permitting the dog 135 to engage with the teeth of the gear 137.

In Fig. 6, I have shown a form of burner mechanism which I consider especially useful. In this type of device a bypass 150 leads from the heated pipe 41 to a supplemental burner 151 situated above the burner casting 15. The stream of heated oil from this burner is adapted to be ignited by sparks passing across the spark gap 152 in close proximity to the orifice of the burner. The function of this supplemental burner is to replace the spark plug 54 and to make certain the ignition of the vapor passing up through the burner casting 15 from the burners 42 or 14. In some instances sparks from the spark plug 54 might not ignite this vapor until an explosive mixture had been created which would wreck the boiler, but there will be an adequate volume of flame from the burner 151 to insure timely ignition of the vapor arising through the burner casting without any possibility of sufficient time elapsing for the formation of an explosive mixture.

It will, of course, be appreciated that the relative time of opening and closing the various valves and switches will depend in any specific instance upon the details of design of various parts, such, for instance, as the storage battery, the heating coil and the motor. With this in view the drawings have been largely diagrammatic in their character since in any case it is an easy matter to ascertain the precise periods during which any part of the mechanism must be operative or inoperative, the sequence of events being substantially that described herein.

While I have illustrated and described only certain specific embodiments of my invention, I realize that it is susceptible of wide application, and I do not desire to be limited to the precise structure shown and described.

Having thus described my invention, I claim:

1. In combination in a device of the character described, a burner, independent means for heating the fuel supplied to the burner, an automatic controller for said heating means and automatic means for governing the supply of the fuel thereto.

2. In combination in a device of the character described, a burner, independent means for heating the fuel supplied to the burner, an automatic controller for said heating means and automatic means for governing the supply of fuel to the burner, said controllers functioning consecutively.

3. In combination in a device of the class described, a main burner, means for heating

the fuel supplied to the main burner including an auxiliary burner, independent means for heating fuel supplied to the auxiliary burner and an automatic controller for the auxiliary burner heating means.

4. In combination in a device of the class described, a main burner, means for heating the fuel supplied to the main burner including an auxiliary burner, independent means for heating the fuel supplied to the auxiliary burner and an automatic controller for the auxiliary burner heating means and for governing the supply of fuel to the auxiliary burner.

15 5. In combination in a device of the class described, a main burner, means for heating the fuel supplied to the main burner including an auxiliary burner, independent means for heating the fuel supplied to the auxiliary burner, an automatic controller for said auxiliary burner heating means and for governing the supply of fuel thereto, and means for automatically igniting the auxiliary burner.

25 6. In combination in a device of the class described, a main burner, means for heating the fuel supplied to the main burner, including an auxiliary burner, independent means for heating the fuel supplied to the auxiliary burner, an automatic controller for said auxiliary burner heating means and for governing the supply of fuel to the auxiliary burner, and means for automatically igniting the auxiliary burner.

35 7. In combination in a device of the class described, a main burner, means for heating the fuel supplied thereto, including an auxiliary burner, independent means for heating the fuel supplied to the auxiliary burner, an automatic controller for said auxiliary burner heating means and for governing the supply of fuel to the auxiliary burner, and means for automatically igniting the auxiliary burner.

40

the supply of fuel thereto, means for automatically igniting said fuel and means for controlling the supply of fuel to the main burner after its heating device becomes 45 operative.

8. In combination in a device of the class described, a main burner, means for heating the fuel supplied thereto including an auxiliary burner, independent means for heating the fuel supplied to the auxiliary burner, an automatic controller for said auxiliary burner heating means and for governing the supply of fuel thereto, means for automatically igniting said fuel and means for automatically controlling the supply of fuel to the main burner after its heating device becomes 50 55 operative.

9. In combination in a device of the class described, a main burner, means for heating 60 the fuel supplied thereto, including an auxiliary burner, means for heating the fuel supplied to the auxiliary burner, means for controlling the supply of fuel thereto, means for igniting the auxiliary burner, means for 65 controlling the supply of fuel to the main burner, and an automatic controller for governing the operation of all of said means.

10. In combination in a device of the class described, a main burner, means for heating 70 the fuel supplied thereto, including an auxiliary burner, means for heating the fuel supplied to the auxiliary burner, means for controlling the supply of fuel thereto, means for igniting the auxiliary burner, means for 75 controlling the supply of fuel to the main burner, an automatic controller for governing the operation of all of said means, means for initiating the operation of said controller, and automatic means for stopping 80 said operation.

JOSEPH C. FULLER.
